Primary Examiner—Stella Reid

[57] CLAIM

The ornamental design for a diaper with a pocket, as shown and described.

DESCRIPTION

FIG. 1 is a top plan view of the diaper with a pocket of the present invention;

FIG. 2 is a bottom plan view of the diaper with a pocket of FIG. 1;

FIG. 3 is a right side elevational view of the diaper with a pocket of FIG. 1;

FIG. 4 is a left side elevational view of the diaper with a pocket of FIG. 1;

FIG. 5 is a front elevational view of the diaper with a pocket of FIG. 1; and

FIG. 6 is a back elevational view of the diaper with a pocket of FIG. 1.

FIG. 7 is a top, front, right side perspective view of the diaper with a pocket of FIG. 1; and,

FIG. 8 is an assembled left side elevational view of the diaper with a pocket of FIG. 1.

The broken line showing of the word in FIGS. 1 and 7 is for illustrative purposes only and forms no part of the claimed design.
